(57) **CLAIM**

The ornamental design for a buckling component applied to a magnetic buckling assembly, as shown and described.

DESCRIPTION

FIG. 1 is a top perspective view of a buckling component; and,

FIG. 2 is a sectional view of the buckling component of FIG. 1 applied to a magnetic buckling assembly along the line A-A.

The dash-dot broken lines shown in the drawings illustrate portions of the buckling component applied to a magnetic buckling assembly. The dot-dashed broken lines shown in the drawings represent the claim boundary. The broken lines form no part of the claimed design.
